UNITED STATES PATENT OFFICE.

JULIUS KAHN, OF YOUNGSTOWN, OHIO, ASSIGNOR TO THE TRUSCON STEEL COMPANY, OF YOUNGSTOWN, OHIO, A CORPORATION OF MICHIGAN.

COMPOSITE BEAM CONSTRUCTION.

Application filed April 29, 1921. Serial No. 465,352.

This invention relates to a novel beam construction for structural work, and particularly to a beam of the composite type wherein steel and concrete are consolidated 5 in an advantageous manner to more effectively assimilate compression and tension strains, while at the same time effecting economies in construction.

To that end, the invention contemplates 10 utilizing structural steel as the tension member of a beam or girder in combination with concrete as the compression member, and arranging said members in such coacting relation as to best distribute and sustain the 15 load stresses. More especially it is proposed so to arrange the structural steel tension member with reference to the concrete that the said tension and compression members are not enclosed one within the other, and 20 also in that way combining structural steel and reinforcement to support the building structure both during and after construction.

Heretofore, in the construction of concrete buildings it has been customary to employ combined steel and concrete beams 25 wherein the tension member has been embedded in and enveloped by the concrete and it has, therefore, been necessary to use temporary supports to sustain the building until the concrete sets. It is, therefore, the purpose of the present invention to so arrange 30 the steel and concrete that the two are securely anchored together, but the steel tension member is wholly without concrete and 35 is utilized as a support for the building both during and after construction, thereby obviating the objections to the former method and also facilitating construction.

Accordingly, it will be apparent that a 40 primary object of the invention is to provide a composite beam wherein the tension and compression members are separate, though securely anchored together to provide in effect a unitary beam or girder structure.

With the above and other objects in view 45 which will more readily appear as the nature of the invention is better understood, the same consists in the novel construction, combination and arrangement of parts hereinafter more fully described, illustrated and claimed.

A preferred and practical embodiment of

the invention is shown in the accompanying drawings in which:—

Figure 1 is a vertical sectional view of a composite beam constructed in accordance with the present invention.

Figure 2 is a vertical sectional view taken on the line 2—2 of Figure 1.

Figure 3 is a detail elevation of a simple embodiment of the invention showing a concrete slab superimposed upon an I-beam and interlocked therewith.

Figure 4 is a detail sectional view taken on the line 4—4 of Figure 3.

Figures 5 and 6 are detail sectional and elevational views illustrating another modification that may be resorted to in carrying out the invention.

Similar reference characters designate corresponding parts throughout the several figures of the drawings.

As indicated, a distinctive feature of the present invention resides in having the structural steel tension member of the beam wholly without the concrete compression member, while at the same time securely anchored thereto so as to be an intimate unit of the beam construction. The anchoring 75 projections or tongues of the tension member are intended to serve not only to positively anchor the tension and compression members of the beam together, but may be so located as to resist the internal shearing 80 stresses in the concrete or compression member of the beam.

To illustrate the improved features of construction reference may be had to the accompanying drawings in which the numeral 90 1 designates the structural steel element, preferably an I-beam having its top flanges sheared at intervals as at 2, permitting anchoring tongues 3 to be struck up from said flanges for embedment in the superimposed concrete body C which constitutes the compression member of the beam. These anchoring tongues 3 are preferably arranged obliquely, and, at the locations of the shear 95 2, the tongues which are struck up from the opposite flanges of the beam are preferably reversely related, therefore being disposed in crossing relation to more effectively operate as anchoring elements and as the shear members of the construction. The upper 100 105 ends of the said tongues 3 are preferably

formed with holding hooks 4 which provide substantial anchoring points for the concrete body of the compression member and also act as holding elements for slab reinforcement 5 where it is desired to use such reinforcement.

From the described construction, it will be apparent that the concrete body C of the compression member is formed directly over and upon the structural steel tension member 1 upon the top flange of the latter, thereby providing an arrangement in which the tension member is located wholly without the concrete body of the compression member, and the beam construction can, therefore, be utilized to support the building both during and after construction without the aid of temporary supports which are necessary where the steel tension member is enveloped by the concrete body of the compression member. The feature of the concrete body of the compression member being formed directly over and upon the structural steel tension member 1 is exemplified in the simple embodiment of the invention shown in Figures 3 and 4, in which the structural steel tension member 1, preferably of I-beam formation has its upwardly projecting tongues 3 embedded and anchored in a superimposed concrete slab C, thereby providing a construction wherein the two members of the composite beam construction are securely fastened together in such a manner as to provide against relative slippage between the two members where they join. As shown in Figures 5 and 6, this construction also admits of the use of steel sections with a large lower flange having the effect of lowering the neutral axis of the composite beam (as well as that of the steel beam) as shown at X—X Fig. 5. The advantage of this construction is the increasing of the effective depth of the beam so that a relatively small sectional area of concrete will suffice.

At the locations in the span of the beam where the girders are required, the concrete body of the compression member is deepened as at 6 to combine with the girder tension member 7 having its top flanges sheared and struck up to provide the anchoring tongues 8 which are enveloped by the concrete body of the compression member, as and for the purpose already described. Figure 1 of the drawings shows a portion of a beam span made up of the composite beam construction described and also includes an illustration of a girder formed with the beam, as a part of the same construction.

As shown in Figure 1 of the drawings, the exposed tension structural member may be covered by a covering 9 of lath and plaster for fireproofing purposes should that be desired or required.

From the foregoing, it is thought that the essential features of the improved beam construction will now be understood, and it will also be apparent that minor changes in the form, proportion and details of construction may be resorted to without departing from the spirit or sacrificing any of the features of the invention.

I claim:

1. A composite beam comprising an I-beam tension member having its body portion in vertical position and one of its flanged portions uppermost and forming an upper bearing surface, a concrete compression member having a bottom surface with a bearing portion substantially coextensive with the top bearing surface of the tension member and resting thereon, said tension member being wholly outside the compression member, and anchoring connections extending from the I-beam and embedded in the overlying concrete compression member.

2. A composite beam comprising an I-beam tension member having its body portion in vertical position with one of its flange portions uppermost and constituting an upper bearing surface, a compression member of concrete overlying the tension member and comprising a body having a depending portion that rests upon the said bearing surface, said tension member being wholly outside the compression member, and anchoring connections extending from the tension member and embedded in the depending portion of the compression member.

3. A composite beam comprising I-beam tension members in crossed relation with one on the other and having their bodies in vertical position and their upper flanges constituting bearing surfaces, a concrete compression member common to the tension members and having depending portions of different depths that respectively rest upon the bearing surfaces formed by the uppermost flanges of the crossed I-beam tension members, said tension members being located outside the compression member, and anchoring connections between the tension members and the depending portions of the compression member.

In testimony whereof I hereunto affix my signature.

JULIUS KAHN.
